PORTABLE DISPENSING REEL FOR ROLLED WIRE

Earl G. Trunkhill, Hettinger, N. Dak.

Application April 26, 1950, Serial No. 158,174

3 Claims. (Cl. 242—129)

1

The present invention relates to new and useful improvements in reels and more particularly to a portable reel for holding rolled wire for dispensing or unrolling desired lengths of wire therefrom.

An important object of the invention is to provide a reel of this character including a vertical spindle supported on a base and in which the reel tapers toward its upper end for easily and quickly placing rolls of wire of various sizes thereon and providing means for holding the roll on the reel and insuring unwinding of the convolutions of the roll in regular order to prevent entanglement of the wire.

A further object of the invention is to provide a novel reel construction wherein the spindle is formed with a flange at its lower end to which the inner ends of radial arms are secured and the arms form supports for upwardly converging legs to provide a tapered upper end for the hub of the reel.

A still further object is to provide a base for the reel formed of a wheel which rests on its side when the reel is in dispensing position and which serves to support and roll the reel from place to place.

A still further object is to provide a device of this character of simple and practical construction, which is efficient and reliable in operation, strong and durable, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view;

Figure 2 is a top plan view;

Figure 3 is a vertical sectional view taken on a line 3—3 of Figure 2;

Figure 4 is an enlarged fragmentary sectional view taken on a line 4—4 of Figure 3; and,

Figure 5 is an enlarged fragmentary vertical sectional view of the friction adjusting cap at the top of the reel.

Referring now to the drawings in detail wherein for the purpose of illustration I have disclosed a preferred embodiment of the invention the numeral 5 designates a base of annular construction and preferably in the form of a wheel having spokes 6 and a hub 7. The wheel is placed on its side to form the base 5 and a standard 50 preferably of tubular construction is fixed at its

upper end in a tapered standard 8 which is rotatable on a vertical spindle 9 which is supported by a bearing assembly 10 and 11. The standard 8 is secured to the lower end of the spindle 9 by a flange 12 and the upper end of the standard 8 is secured to a cap 13 which is secured to the upper end of the spindle 9 by a lock washer 14 and a lock nut 15.

Horizontal arms 16 are secured to the spindle 9 at their inner ends by a bolt 17 and nut 18 and are secured at their lower ends to the outer portion of the arms 14 by bolts 19 and nuts 20 and the upper end of the arms 16 converges to form an upwardly tapering reel 21.

The upper end of the arms 16 is secured to the under side of a frusto-conical cap 22 by bolts 23 and nuts 24.

The cap 22 is formed with a flat top 25 which rests on the upper end of the spindle 9 and a self-lubricating washer 26 is placed on the flat top 25.

With the cap 22 in place a metal washer 27 is placed on top of washer 26 and a lock washer 28 is secured to the top of washer 27 by a lock nut 29.

With the lock washer 28 in place a screw 30 is threaded into the top of washer 27 and a wheel 31 is secured to the top of screw 30.

With the wheel 31 in place a substantially dome-shaped cap plate 32 is placed on top of the wheel 31 and a screw 33 is threaded into the top of the cap plate 32.

With the cap plate 32 in place a wire 34 is wound around the reel 21 and the wire 34 is held in place by a wire 35 which is wound around the wire 34.

With the wire 35 in place a wire 36 is wound around the wire 35 and the wire 36 is held in place by a wire 37 which is wound around the wire 36.

With the wire 37 in place a wire 38 is wound around the wire 37 and the wire 38 is held in place by a wire 39 which is wound around the wire 38.

With the wire 39 in place a wire 40 is wound around the wire 39 and the wire 40 is held in place by a wire 41 which is wound around the wire 40.

With the wire 41 in place a wire 42 is wound around the wire 41 and the wire 42 is held in place by a wire 43 which is wound around the wire 42.

With the wire 43 in place a wire 44 is wound around the wire 43 and the wire 44 is held in place by a wire 45 which is wound around the wire 44.

With the wire 45 in place a wire 46 is wound around the wire 45 and the wire 46 is held in place by a wire 47 which is wound around the wire 46.

With the wire 47 in place a wire 48 is wound around the wire 47 and the wire 48 is held in place by a wire 49 which is wound around the wire 48.

With the wire 49 in place a wire 50 is wound around the wire 49 and the wire 50 is held in place by a wire 51 which is wound around the wire 50.

With the wire 51 in place a wire 52 is wound around the wire 51 and the wire 52 is held in place by a wire 53 which is wound around the wire 52.

With the wire 53 in place a wire 54 is wound around the wire 53 and the wire 54 is held in place by a wire 55 which is wound around the wire 54.

With the wire 55 in place a wire 56 is wound around the wire 55 and the wire 56 is held in place by a wire 57 which is wound around the wire 56.

With the wire 57 in place a wire 58 is wound around the wire 57 and the wire 58 is held in place by a wire 59 which is wound around the wire 58.

With the wire 59 in place a wire 60 is wound around the wire 59 and the wire 60 is held in place by a wire 61 which is wound around the wire 60.

With the wire 61 in place a wire 62 is wound around the wire 61 and the wire 62 is held in place by a wire 63 which is wound around the wire 62.

With the wire 63 in place a wire 64 is wound around the wire 63 and the wire 64 is held in place by a wire 65 which is wound around the wire 64.

With the wire 65 in place a wire 66 is wound around the wire 65 and the wire 66 is held in place by a wire 67 which is wound around the wire 66.

With the wire 67 in place a wire 68 is wound around the wire 67 and the wire 68 is held in place by a wire 69 which is wound around the wire 68.

With the wire 69 in place a wire 70 is wound around the wire 69 and the wire 70 is held in place by a wire 71 which is wound around the wire 70.

With the wire 71 in place a wire 72 is wound around the wire 71 and the wire 72 is held in place by a wire 73 which is wound around the wire 72.

With the wire 73 in place a wire 74 is wound around the wire 73 and the wire 74 is held in place by a wire 75 which is wound around the wire 74.

With the wire 75 in place a wire 76 is wound around the wire 75 and the wire 76 is held in place by a wire 77 which is wound around the wire 76.

With the wire 77 in place a wire 78 is wound around the wire 77 and the wire 78 is held in place by a wire 79 which is wound around the wire 78.

With the wire 79 in place a wire 80 is wound around the wire 79 and the wire 80 is held in place by a wire 81 which is wound around the wire 80.

With the wire 81 in place a wire 82 is wound around the wire 81 and the wire 82 is held in place by a wire 83 which is wound around the wire 82.

With the wire 83 in place a wire 84 is wound around the wire 83 and the wire 84 is held in place by a wire 85 which is wound around the wire 84.

With the wire 85 in place a wire 86 is wound around the wire 85 and the wire 86 is held in place by a wire 87 which is wound around the wire 86.

With the wire 87 in place a wire 88 is wound around the wire 87 and the wire 88 is held in place by a wire 89 which is wound around the wire 88.

With the wire 89 in place a wire 90 is wound around the wire 89 and the wire 90 is held in place by a wire 91 which is wound around the wire 90.

With the wire 91 in place a wire 92 is wound around the wire 91 and the wire 92 is held in place by a wire 93 which is wound around the wire 92.

With the wire 93 in place a wire 94 is wound around the wire 93 and the wire 94 is held in place by a wire 95 which is wound around the wire 94.

With the wire 95 in place a wire 96 is wound around the wire 95 and the wire 96 is held in place by a wire 97 which is wound around the wire 96.

With the wire 97 in place a wire 98 is wound around the wire 97 and the wire 98 is held in place by a wire 99 which is wound around the wire 98.

With the wire 99 in place a wire 100 is wound around the wire 99 and the wire 100 is held in place by a wire 101 which is wound around the wire 100.

With the wire 101 in place a wire 102 is wound around the wire 101 and the wire 102 is held in place by a wire 103 which is wound around the wire 102.

With the wire 103 in place a wire 105 is wound around the wire 103 and the wire 105 is held in place by a wire 106 which is wound around the wire 105.

With the wire 106 in place a wire 107 is wound around the wire 106 and the wire 107 is held in place by a wire 108 which is wound around the wire 107.

With the wire 108 in place a wire 109 is wound around the wire 108 and the wire 109 is held in place by a wire 110 which is wound around the wire 109.

With the wire 110 in place a wire 111 is wound around the wire 110 and the wire 111 is held in place by a wire 112 which is wound around the wire 111.

With the wire 112 in place a wire 113 is wound around the wire 112 and the wire 113 is held in place by a wire 114 which is wound around the wire 113.

With the wire 114 in place a wire 115 is wound around the wire 114 and the wire 115 is held in place by a wire 116 which is wound around the wire 115.

With the wire 116 in place a wire 117 is wound around the wire 116 and the wire 117 is held in place by a wire 118 which is wound around the wire 117.

With the wire 118 in place a wire 119 is wound around the wire 118 and the wire 119 is held in place by a wire 120 which is wound around the wire 119.

With the wire 120 in place a wire 121 is wound around the wire 120 and the wire 121 is held in place by a wire 122 which is wound around the wire 121.

With the wire 122 in place a wire 123 is wound around the wire 122 and the wire 123 is held in place by a wire 124 which is wound around the wire 123.

With the wire 124 in place a wire 125 is wound around the wire 124 and the wire 125 is held in place by a wire 126 which is wound around the wire 125.

With the wire 126 in place a wire 127 is wound around the wire 126 and the wire 127 is held in place by a wire 128 which is wound around the wire 127.

With the wire 128 in place a wire 129 is wound around the wire 128 and the wire 129 is held in place by a wire 130 which is wound around the wire 129.

With the wire 130 in place a wire 131 is wound around the wire 130 and the wire 131 is held in place by a wire 132 which is wound around the wire 131.

With the wire 132 in place a wire 133 is wound around the wire 132 and the wire 133 is held in place by a wire 134 which is wound around the wire 133.

With the wire 134 in place a wire 135 is wound around the wire 134 and the wire 135 is held in place by a wire 136 which is wound around the wire 135.

With the wire 136 in place a wire 137 is wound around the wire 136 and the wire 137 is held in place by a wire 138 which is wound around the wire 137.

With the wire 138 in place a wire 139 is wound around the wire 138 and the wire 139 is held in place by a wire 140 which is wound around the wire 139.

With the wire 140 in place a wire 141 is wound around the wire 140 and the wire 141 is held in place by a wire 142 which is wound around the wire 141.

With the wire 142 in place a wire 143 is wound around the wire 142 and the wire 143 is held in place by a wire 144 which is wound around the wire 143.

With the wire 144 in place a wire 145 is wound around the wire 144 and the wire 145 is held in place by a wire 146 which is wound around the wire 145.

With the wire 146 in place a wire 147 is wound around the wire 146 and the wire 147 is held in place by a wire 148 which is wound around the wire 147.

With the wire 148 in place a wire 149 is wound around the wire 148 and the wire 149 is held in place by a wire 150 which is wound around the wire 149.

With the wire 150 in place a wire 151 is wound around the wire 150 and the wire 151 is held in place by a wire 152 which is wound around the wire 151.

With the wire 152 in place a wire 153 is wound around the wire 152 and the wire 153 is held in place by a wire 154 which is wound around the wire 153.

With the wire 154 in place a wire 155 is wound around the wire 154 and the wire 155 is held in place by a wire 156 which is wound around the wire 155.

With the wire 156 in place a wire 157 is wound around the wire 156 and the wire 157 is held in place by a wire 158 which is wound around the wire 157.

With the wire 158 in place a wire 159 is wound around the wire 158 and the wire 159 is held in place by a wire 160 which is wound around the wire 159.

With the wire 160 in place a wire 161 is wound around the wire 160 and the wire 161 is held in place by a wire 162 which is wound around the wire 161.

With the wire 162 in place a wire 163 is wound around the wire 162 and the wire 163 is held in place by a wire 164 which is wound around the wire 163.

With the wire 164 in place a wire 165 is wound around the wire 164 and the wire 165 is held in place by a wire 166 which is wound around the wire 165.

With the wire 166 in place a wire 167 is wound around the wire 166 and the wire 167 is held in place by a wire 168 which is wound around the wire 167.

With the wire 168 in place a wire 169 is wound around the wire 168 and the wire 169 is held in place by a wire 170 which is wound around the wire 169.

With the wire 170 in place a wire 171 is wound around the wire 170 and the wire 171 is held in place by a wire 172 which is wound around the wire 171.

With the wire 172 in place a wire 173 is wound around the wire 172 and the wire 173 is held in place by a wire 174 which is wound around the wire 173.

With the wire 174 in place a wire 175 is wound around the wire 174 and the wire 175 is held in place by a wire 176 which is wound around the wire 175.

With the wire 176 in place a wire 177 is wound around the wire 176 and the wire 177 is held in place by a wire 178 which is wound around the wire 177.

With the wire 178 in place a wire 179 is wound around the wire 178 and the wire 179 is held in place by a wire 180 which is wound around the wire 179.

With the wire 180 in place a wire 181 is wound around the wire 180 and the wire 181 is held in place by a wire 182 which is wound around the wire 181.

With the wire 182 in place a wire 183 is wound around the wire 182 and the wire 183 is held in place by a wire 184 which is wound around the wire 183.

With the wire 184 in place a wire 185 is wound around the wire 184 and the wire 185 is held in place by a wire 186 which is wound around the wire 185.

With the wire 186 in place a wire 187 is wound around the wire 186 and the wire 187 is held in place by a wire 188 which is wound around the wire 187.

With the wire 188 in place a wire 189 is wound around the wire 188 and the wire 189 is held in place by a wire 190 which is wound around the wire 189.

With the wire 190 in place a wire 191 is wound around the wire 190 and the wire 191 is held in place by a wire 192 which is wound around the wire 191.

With the wire 192 in place a wire 193 is wound around the wire 192 and the wire 193 is held in place by a wire 194 which is wound around the wire 193.

With the wire 194 in place a wire 195 is wound around the wire 194 and the wire 195 is held in place by a wire 196 which is wound around the wire 195.

With the wire 196 in place a wire 197 is wound around the wire 196 and the wire 197 is held in place by a wire 198 which is wound around the wire 197.

With the wire 198 in place a wire 199 is wound around the wire 198 and the wire 199 is held in place by a wire 200 which is wound around the wire 199.

With the wire 200 in place a wire 201 is wound around the wire 200 and the wire 201 is held in place by a wire 202 which is wound around the wire 201.

With the wire 202 in place a wire 203 is wound around the wire 202 and the wire 203 is held in place by a wire 204 which is wound around the wire 203.

With the wire 204 in place a wire 205 is wound around the wire 204 and the wire 205 is held in place by a wire 206 which is wound around the wire 205.

With the wire 206 in place a wire 207 is wound around the wire 206 and the wire 207 is held in place by a wire 208 which is wound around the wire 207.

With the wire 208 in place a wire 209 is wound around the wire 208 and the wire 209 is held in place by a wire 210 which is wound around the wire 209.

With the wire 210 in place a wire 211 is wound around the wire 210 and the wire 211 is held in place by a wire 212 which is wound around the wire 211.

With the wire 212 in place a wire 213 is wound around the wire 212 and the wire 213 is held in place by a wire 214 which is wound around the wire 213.

With the wire 214 in place a wire 215 is wound around the wire 214 and the wire 215 is held in place by a wire 216 which is wound around the wire 215.

With the wire 216 in place a wire 217 is wound around the wire 216 and the wire 217 is held in place by a wire 218 which is wound around the wire 217.

With the wire 218 in place a wire 219 is wound around the wire 218 and the wire 219 is held in place by a wire 220 which is wound around the wire 219.

With the wire 220 in place a wire 221 is wound around the wire 220 and the wire 221 is held in place by a wire 222 which is wound around the wire 221.

With the wire 222 in place a wire 223 is wound around the wire 222 and the wire 223 is held in place by a wire 224 which is wound around the wire 223.

With the wire 224 in place a wire 225 is wound around the wire 224 and the wire 225 is held in place by a wire 226 which is wound around the wire 225.

With the wire 226 in place a wire 227 is wound around the wire 226 and the wire 227 is held in place by a wire 228 which is wound around the wire 227.

With the wire 228 in place a wire 229 is wound around the wire 228 and the wire 229 is held in place by a wire 230 which is wound around the wire 229.

With the wire 230 in place a wire 231 is wound around the wire 230 and the wire 231 is held in place by a wire 232 which is wound around the wire 231.

With the wire 232 in place a wire 233 is wound around the wire 232 and the wire 233 is held in place by a wire 234 which is wound around the wire 233.

With the wire 234 in place a wire 235 is wound around the wire 234 and the wire 235 is held in place by a wire 236 which is wound around the wire 235.

With the wire 236 in place a wire 237 is wound around the wire 236 and the wire 237 is held in place by a wire 238 which is wound around the wire 237.

With the wire 238 in place a wire 239 is wound around the wire 238 and the wire 239 is held in place by a wire 240 which is wound around the wire 239.

With the wire 240 in place a wire 241 is wound around the wire 240 and the wire 241 is held in place by a wire 242 which is wound around the wire 241.

With the wire 242 in place a wire 243 is wound around the wire 242 and the wire 243 is held in place by a wire 244 which is wound around the wire 243.

With the wire 244 in place a wire 245 is wound around the wire 244 and the wire 245 is held in place by a wire 246 which is wound around the wire 245.

With the wire 246 in place a wire 247 is wound around the wire 246 and the wire 247 is held in place by a wire 248 which is wound around the wire 247.

With the wire 248 in place a wire 249 is wound around the wire 248 and the wire 249 is held in place by a wire 250 which is wound around the wire 249.

With the wire 250 in place a wire 251 is wound around the wire 250 and the wire 251 is held in place by a wire 252 which is wound around the wire 251.

With the wire 252 in place a wire 253 is wound around the wire 252 and the wire 253 is held in place by a wire 254 which is wound around the wire 253.

With the wire 254 in place a wire 255 is wound around the wire 254 and the wire 255 is held in place by a wire 256 which is wound around the wire 255.

</div

though there is herein shown and described a preferred embodiment of the invention the same is susceptible to certain changes fully comprehended by the spirit of the invention as herein described and the scope of the appended claims.

Having described the invention, what is claimed as new is:

1. A portable dispensing device for rolls of wire comprising a base, a standard rising from the base, and a reel rotatably mounted on the standard and including horizontal arms at the lower end of the reel, upwardly inclined legs rising from the horizontal arms and converging at the upper end of the reel, a hollow conical cap for the upper ends of said legs in which said upper ends are attached, and screw feed means for exerting variable pressure downwardly against said cap to variably restrict rotation of said reel.

2. A portable dispensing device for rolls of wire comprising a base, a standard rising from the base, a spindle rotatably mounted on the standard, radial arms projecting horizontally at the lower end of the spindle, legs supported at their lower ends on the arms and converging at the top of the spindle, pegs secured in vertically adjusted position on the legs and overlying a roll of wire placed on the reel, and a conical cap surmounting said spindle and rotatable on said standard with the upper ends of said legs fixed therein.

3. A portable dispensing device for rolls of wire

comprising a wheel resting on its side to form a base, a standard rising from the hub of the wheel, a spindle rotatable on the standard, a horizontal flange at the lower end of the spindle, radial arms attached to said flange, legs supported at their lower ends on said arms and converging at their upper ends to a tapered reel construction, a conical cap surmounting said spindle and rotatable on said standard with the upper ends of said legs fixed therein, and screw feed means on the upper end of said standard for exerting variable pressure against said cap to variably restrict rotation of said reel.

EARL G. TRUNKHILL.
